United States Patent Office

Des. 221,429

Patented Aug. 17, 1971

221,429

SWING SPOUT

Tor Petterson, San Pedro, Calif., assignor to
Lloyd Spencer, Pasadena, Calif.

Filed May 8, 1970, Ser. No. 22,896

Term of patent 14 years

Int. Cl. D23—01

U.S. Cl. D23—32

FIG. 1 is a perspective view of the swing spout, taken from above and from one side.

FIG. 2 is a perspective view thereof, taken from below and from one side.

FIG. 3 is a side view thereof.

FIG. 4 is a sectional view thereof, taken through 4—4 of FIG. 3.

FIG. 5 is a sectional view thereof, taken through 5—5 of FIG. 3.

I claim:

The ornamental design for a swing spout, as shown.
